SAFETY DEVICE FOR TOOLS

Filed Mar. 12, 1921

UNITED STATES PATENT OFFICE.

JAMES E. MCGUIRE, OF CAMDEN, NEW JERSEY.

SAFETY DEVICE FOR TOOLS.

Application filed March 12, 1921. Serial No. 451,726.

To all whom it may concern:

Be it known that I, JAMES E. MCGUIRE, a citizen of the United States, residing at Camden, in the county of Camden and State 5 of New Jersey, have invented certain new and useful Improvements in Safety Devices for Tools, of which the following is a specification, reference being had to the accompanying drawings.

10 This invention relates to improvements in safety devices for tools, and has for a particular object thereof the provision of means whereby a tool may be secured to an inclined or vertical surface to prevent its falling 15 therefrom.

A further object of the invention is to provide a device of this character which is normally completely concealed in the tool handle in order that the same may not interfere with the proper and efficient use of 20 the tool.

A still further object of the invention is to provide a device of this character which is of sufficient strength of structure to hold 25 the tool sufficiently firmly to the surface to which it is attached to permit of the workman grasping the tool to support himself if he should slip.

Other objects and advantages of the invention will become apparent throughout 30 the course of the following description.

In the accompanying drawings wherein for the purpose of illustration is shown a preferred embodiment of my invention, and 35 wherein like reference characters designate like parts throughout:

Figure 1 is a side elevation partially in section showing a saw having a device constructed in accordance with my invention 40 employed for holding the saw in position upon an inclined surface;

Figure 2 is a longitudinal sectional view taken through my device;

Figure 3 is a transverse sectional view 45 therethrough, and

Figure 4 is a fragmentary side elevation of a saw and the handle thereof showing my safety device applied to the handle.

Referring now more particularly to the 50 drawings, the numeral 10 indicates a casing adapted to be seated in a recess R formed in the handle of a tool T, the casing being provided with an enlarged portion 11 and having openings formed in the ends thereof for 55 the reception of securing means 12 and 12^a

whereby the casing may be held in position, the upper surface of the casing being flush with the surface of the tool handle. The casing has pivoted therein, as at 13, a spike member 14 which is triangular in cross section and which normally has the outer face thereof flush with the upper surface of the casing, the casing being grooved for the reception of the spike. At the opposite side of the pivot point from the piercing point 14^a of the spike, the under surface of the spike is provided with a flattened portion 15, and the upper surface thereof is enlarged to form a finger engaging portion 16.

When the casing is mounted in the handle, 70 a spring 17 is disposed beneath the casing and held in position by the securing means 12, and at its free end extending beneath and engaging the flattened portion 15 of the spike member 14 so that when the spike member is rotated about the pivot 13 thereof the flattened portion 15 of the spike engaging the spring deforms the same and accordingly when the finger engaging portion 16 is released, if the spike member is not 80 engaged in any surface it will immediately return to its normal position concealed within the handle. This operation likewise takes place when the tool is removed from a place where it has been secured by the spike. In 85 the use of the device, if the operator desires to secure the tool against slipping he presses his finger against the enlargement or finger engagement portion 16 so that the point of the spike 14 is separated from the side of 90 the tool, as indicated by dotted lines in Figure 2. While held in this position the spike is readily engaged with any surface desired. Due to the peculiar shaping of the point, any strain placed upon the tool will tend to 95 force the spike more firmly into the surface.

From the foregoing it is believed to be obvious that I have constructed a safety device for use with a tool which is particularly well adapted for such use by reason of 100 the fact that when not in use it is completely hidden within the handle of the tool and does not interfere in any manner with the operation thereof. It will furthermore be obvious that the construction as hereinabove 105 set forth is capable of some change and modification without departing from the spirit of my invention and I accordingly do not limit myself to such specific structure except as hereinafter claimed.

What I claim is:

1. The combination with a tool handle having a recess formed therein, of a pivoted spike member mounted in the recess, and yieldable means normally acting to throw said spike member to inoperative position with the upper face thereof flush with the surface of the tool handle.
2. The combination with a tool handle having a recess formed therein, of a casing mounted within the recess and substantially flush with the surface of the tool handle, a spike member pivoted within the casing, and a spring normally acting to throw said spike member to inoperative position with the upper surface thereof flush with the upper surface of the casing.
3. The combination with a tool handle having a recess formed therein, of a pivoted spike member mounted in the recess, and yieldable means normally acting to throw said spike member to inoperative position with the upper face thereof flush with the surface of the tool handle, said spike mem-
ber being tapered throughout its length and 25
being triangular in cross section.
4. The combination with a tool handle having a recess formed therein, of a casing mounted within the recess and substantially flush with the surface of the tool handle, a 30
spike member pivoted within the casing, and a spring normally acting to throw said spike member to inoperative position with the upper surface thereof flush with the upper surface of the casing, said spike member being 35
tapered throughout its length and being triangular in cross section.
5. The combination with a tool handle having a recess formed therein, of a pivoted spike member mounted in the recess, means 40
normally acting to throw said spike member to inoperative position in the recess, and a finger piece on the spike member for throwing the same to operative position against the action of the aforesaid means.

In testimony whereof I hereunto affix my
signature.

JAMES E. McGUIRE.
